T. S. MASON

MEGAPHONE

Filed March 10, 1925

INVENTOR.
T. S. MASON,
BY *Marvin Co.*
ATTORNEYS.

UNITED STATES PATENT OFFICE.

THOMAS S. MASON, OF HARTFORD, CONNECTICUT.

MEGAPHONE.

Application filed March 10, 1925. Serial No. 14,524.

To all whom it may concern:

Be it known that I, THOMAS S. MASON, a citizen of the United States, residing at Hartford, in the county of Hartford, State 5 of Connecticut, have invented certain new and useful Improvements in Megaphones, of which the following is a specification.

This invention relates to an improved megaphone especially adapted for use by college cheer leaders and rooters, although, 10 of course, also adapted for other uses.

The object of the invention is to provide a megaphone of this character which may be used not only to magnify and amplify the 15 voice of the cheer leader or person using the megaphone but which may be used also for the purpose of prominently displaying the college colors and for the purpose of producing musical sounds and demonstrative 20 noises along with merry-making or demonstrative motions or gestures.

A further object is the provision of a megaphone of this character which has these advantages and capacities while still preserving 25 the general form and appearance of an ordinary megaphone and while still presenting a simple and durable construction, which is easily handled and which is comparatively inexpensive to manufacture.

Other objects and advantages reside in 30 certain novel features of the construction, arrangement and combination of parts which will be hereinafter more fully described and particularly pointed out in the 35 appended claims, reference being had to the accompanying drawings forming a part of this specification, and in which:

Figure 1 is a perspective view showing 40 one embodiment of the invention,

Figure 2 is a view in end elevation looking 45 to the left of Figure 1,

Figure 3 is a view in transverse section taken on the line 3—3 of Figure 2, and

Figure 4 is a detail perspective view of the 45 musical plate employed in the musical device used in the mouthpiece of the megaphone.

Referring to the drawings, the numeral 1 50 designates generally a megaphone which has the usual annular mouthpiece 2 at the small end of a flaring body 3, the megaphone serving to amplify the voice of the person using the same in the usual and ordinary way. In the mouthpiece 2 a musical device or instrument, designated generally at 4, is provided

and preferably is of segmental form and is located within and fixed to the mouthpiece 2. The musical instrument or device 4 is adapted to produce musical sounds and may be of any suitable type. Preferably it comprises a body portion 5 having a passage 6 therethrough. A musical plate 7 is fixed to the body portion 5 and is provided with a sound reed 8 similar to blades used on harmonicas. The reed 8 is located in the passage 6 so that by blowing in the passage the musical device may be sounded. Of course, more than one passage 6 and more than one reed 8 may be employed if found desirable.

At the large end of the flaring body 3 of the megaphone, a slot or opening 10 is formed and is adapted to receive ribbons 11 which correspond to the college colors and which are knitted, as at 12, to secure the same in the slot or opening. A cow-bell 13 is 75 fixed to the ribbon so that when the megaphone is waved the college colors are displayed and the cow-bell is sounded. The megaphone may be used by the cheer leaders in the ordinary way, it may be used to 80 produce musical sounds by operating the device 4, and it may be used to display the college colors while sounding the cow-bell.

As shown in the drawings the ribbons or streamers 11 may hang from the outside of the body 3 of the megaphone but it is to be understood that these streamers or ribbons may be disposed within and hang out of the large end of the megaphone after passing through the slot or opening 10 and being suitably secured to the bell 13, the ribbons or streamers being suitably knotted or otherwise fashioned or entwined to prevent their sliding through the opening 10 when they are disposed within the megaphone and hang out of the large end thereof.

I claim:

1. A megaphone including a flaring body and a mouthpiece at the small end of the body, and a musical device placed at the 100 mouthpiece and occupying only a portion of the transverse extent thereof so that the mouthpiece may be used to sound the musical instrument or to employ the megaphone in the ordinary way.

2. A megaphone including a flaring body portion having an annular mouthpiece at its small end and a musical instrument of segmental form fitted in and secured to the mouthpiece and occupying only a portion of 110

the transverse extent thereof whereby the musical instrument may be sounded or the megaphone used from the mouthpiece.

3. A megaphone including a flaring body portion having an annular mouthpiece at its small end and a musical instrument of segmental form fitted in and secured to the mouthpiece and occupying only a portion of the transverse extent thereof whereby the

musical instrument may be sounded or the megaphone used from the mouthpiece, said musical instrument including a body portion having a passage, and a musical plate fastened to the body portion and slotted and having a feed adjacent the slot and located in the passage of the body portion.

THOMAS S. MASON.
